UNITED STATES PATENT OFFICE

1,990,743

BOILER

William McGuiness, Chicago, Ill.

Original application March 14, 1933, Serial No. 660,662. Divided and this application March 21, 1934, Serial No. 716,661

3 Claims. (Cl. 122—359)

This invention is a division of my patent application, Serial No. 660,662, filed March 14, 1933, entitled "Boilers" patented May 15, 1934, Patent No. 1,959,033.

5 The invention particularly pertains to water tube boilers adapted for hot water heating systems and low pressure steam heating systems respectively.

The object of the invention is to provide the 10 water tube system which is positioned entirely within the combustion chamber of the boiler with additional circulating tubes of novel design, which do not only increase the water circulation and heat exchange, but also reinforce the entire 15 water tube system mechanically.

Still another object of the invention is to provide a water tube boiler which may be easily assembled and maintained, is cheap to manufacture, is very efficient and safe in operation 20 and is very economical in fuel consumption.

In the drawings:

Fig. 1 is a vertical longitudinal section of the 25 boiler substantially on the line 1—1 of Figure 2, certain portions being shown as broken away.

Fig. 2 is a vertical cross-section of the boiler substantially on the line 2—2 of Figure 1, and

Fig. 3 shows diagrammatically a perspective view of the furnace, the travel of the combustion gases being indicated by arrows.

30 According to the drawings, the boiler of the present invention is provided with a front wall 5, side walls 6 and 7, a rear wall 8 and a top wall 9. The walls 5, 6, 7 and 8 are connected together at their vertical edges and are mounted on a suitable foundation 10 made from refractory material, fire proof brick, cement, torpedo gravel or the like. This foundation 10 contains the ash pit 11 and the grate 12 of the

35 boiler, the front wall of said foundation being provided with the customary draft panel door 13 which permits access to the ash pit 11 and the regulation of the natural draft in the boiler. Within the space confined by the front, side and rear walls is arranged an inner casing comprising the vertical walls 14, 15, 16 and 17.

40 These inner walls extend the full height of the outer walls 5, 6, 7 and 8 and are spaced from the outer vertical walls to form an annular gas chamber 18 which extends around the entire inner casing and is used as a flue through which the combustion gases are conducted before being discharged into the chimney. Within the inner casing are arranged the fire box 19, the lower receivers 20 and 21, the upper receiver 22 and the water tubes 23 connecting the lower receiv-

ers with the upper receiver. The lower portion of the inner casing surrounds the fire box 19 into which fuel may be introduced through a door 24 arranged in the outer front wall 5 and an opening 25 in the front wall 14 of the inner casing. The outer front wall 5 is also provided with a door 26 through which the clinker may be removed from the grate 12.

5 The upper end of the inner casing is closed by the top wall 9. The side wall 15 of the inner casing has near its upper end a longitudinal opening 27 through which the hot combustion gases are conducted into the annular air chamber 18. A baffle plate 28 extending along the upper horizontal edge of the opening 27 directs the hot gases downwardly into the air space between the walls 15 and 6. Within this air space is arranged near the rear end of the same an upwardly extending baffle plate 29 which completely bridges the distance between the inner wall 15 and the outer side wall 6 and directs the hot gases forwardly toward the front of the boiler.

10 According to Fig. 3 there is arranged in the air space between the front wall 14 of the inner casing and the outer front wall 5 a partition wall 30 which is positioned to the left hand side of the opening 25 in the wall 14 and extends vertically downward from the top wall 9 to a point somewhat below the lower edge of the opening 25. This vertical partition 30 is connected with a horizontal partition 31, which extends along the lower edge of the opening 25 and is then bent vertically upward at 32 at the right hand side of the same to terminate in an 15 outwardly inclined portion 33.

20 The partition wall 30, 31, 32, 33 divides the air space between the wall 14 and 5 into two superposed chambers or flues. The hot gases flowing in the air space between the walls 15 and 6 forwardly are divided by the horizontal wall portion 31 into two currents. The upper current, which contains the hotter gases, is conducted by the partition wall into the opening 25 in the front wall 14 and therefore re-enters the combustion zone of the boiler. The lower current, which contains cooler gases, is directed past the front of the boiler into the air space between the side walls 7 and 16. This air space 25 extends the entire height of the walls 7 and 16 and permits an expansion of the combustion gases before they are discharged into the chimney 34. The chimney 34 is preferably connected with the lower left hand corner (Fig. 2 and 3) 30

of the air space between the inner rear wall 17 and the outer rear wall 8 as shown at 35.

Referring now to the water tube system of the boiler, the lower receivers 20 and 21 are preferably circular in cross-section and are positioned in the lower left and right hand corner of the inner casing, extending horizontally from the front toward the rear of the boiler. These receiver tubes 20 and 21 project outwardly from the front wall 5 and rear wall 8 respectively and their ends are flanged and are closed by removable cover plates 40 which facilitate cleaning of the receivers. The upper receiver 22 in which the steam separates from the water when the boiler is used for a steam or vapor heating system, is of larger diameter than the lower receivers 20 and 21 and is arranged centrally in the upper portion of the inner casing, just below the top wall 9, extending horizontally from the front toward the rear of the boiler. The ends of said upper receiver 22 extend through the outer front and rear walls 5 and 8 respectively and are likewise flanged and provided with removable cover plates 40. Both lower receivers 20 and 21 are connected with the upper receiver 22 by a series of water tubes 23 of novel formation and arrangement. The water tubes 23 in each row are spaced from one another in longitudinal direction of the receivers, and one row is staggered with respect to the other row in order that the upper portions of the water tubes 23 may be arranged in interlinked relation as will be described presently. The distance between each two water tubes 23 in each row is at least as large as or larger than the outside diameter of one water tube 23. Since all water tubes 23 are arranged and bent in similar manner, it is deemed sufficient when only one water tube is described in detail. The lower end of the water tube 23 is welded into the upper wall of the lower receiver 20 or 21 as the case may be, and extends vertically upwardly approximately to the height in which the upper edge of the opening 25 is located. Then the tube 23 is bent almost horizontally toward the opposite side wall of the inner casing, when it is bent upwardly and backwardly to form a semi-circular bend as shown at 42. The tube 23 extends again almost horizontally toward the opposite side wall of the inner casing and after forming another semicircular bend 43 it is welded into the lower wall of the upper receiver 22. Attention is called to the fact, that the upper end of the sinuously bent tubes 23 are connected to the same side of the upper receiver 22 on which the corresponding lower receiver 20 or 21 is located, in order to facilitate repairs and replacements. Furthermore, it is to be noted, that those tube sections which extend transversely of the inner casing from one side wall to the other are not arranged absolutely horizontal, but they are positioned somewhat inclined in order to prevent any accumulation of sediment in these portions of the water tubes. While I have shown water tubes with two semi-circular bends, it is, of course, obvious that more or less bends may be provided, to increase or decrease the heating surface of the boiler. It is also obvious, that instead of connecting each lower receiver with one row of water tubes to the upper receiver, I may arrange two or more rows of water tubes connecting each lower receiver with the upper receiver. All these modifications are within the scope of my invention.

In the above described manner, all the water tubes 23 are arranged in closely nested relation within the inner casing in which the combustion of the fuel takes place. The hot combustion gases which flow upwardly have to pass along and through the slot-like spaces formed between the two sets of water tubes before leaving the inner casing through the opening 27, so that the water tubes 23 and upper receiver 22 are heated very efficiently, speedily and economically.

In addition to the two series of water tubes 23, there are provided within the inner casing, adjacent the front wall 14 and rear wall 17 thereof specially constructed circulating tubes 45 which enhance the circulation of the water in the boiler and also reinforce the entire water tube system. Each circulating tube 45 comprises a vertical tube section 46 connected with its upper end to the bottom wall of the upper receiver 22 and having its lower end divided in two branches 47 and 48 which extend horizontally and then again vertically downwardly to be connected with their lower ends to the lower receivers 20 and 21 respectively. Furthermore, the lower ends of said branch tubes 47 and 48 are connected with one another by a horizontal tube 49 (Fig. 2). These circulating tubes 45 preferably have a larger diameter than the water tubes 23.

The upper receiver 22 has at its ends, in the top wall thereof upwardly extending fittings 50 and 51 respectively which project through the top wall 9 and are connected with the ends of a steam or hot water header 52. The header 52 is provided with flanged openings 53 and 54 adapted to be connected to a hot water heating system or a steam heating system or the like, it being understood that the boiler may be used with either one of the two heating systems mentioned. In order to supply the boiler with water, one of the lower receivers 20 or 21 is connected by a pipe 54' with a source of water supply, e. g., a water main. A blow off valve is indicated at 55.

While the boiler in the described embodiment is provided with a furnace using hard or soft coal or other solid fuel, I also contemplate to equip the boiler with any other heating device, as for instance an oil burner or a burner for gaseous fuel. Regardless of what kind of a fuel will be used in the operation of the boiler, there will always be obtained a great saving of fuel. Furthermore, the boiler is very compact when assembled and requires very little space. For the average home it may be completely assembled at the factory and may be installed very readily and conveniently, as it may be brought in through any average door, so that it is not necessary to tear down permanent walls or the like in order to install the boiler.

Having thus described my invention, what I claim is:

1. In combination with a boiler having within a casing a fire box and a combustion chamber, of a tubular receiver positioned horizontally in the upper portion of said combustion chamber, two tubular receivers arranged horizontally in the lower portion of said combustion chamber, one at each side of said fire box, said tubular receivers extending with their ends outwardly from said casing and being closed by individually removable cover plates, a plurality of series of water tubes connecting said lower receivers with said upper receiver, said water tubes

being bent sinuously back and forth transversely from one side of combustion chamber to the other, the water tubes in each series of tubes being spaced from one another to form slots through which the other series of tubes and the combustion gases may pass, and circulating tubes adjacent the front and rear ends of said receivers and positioned within said casing, each circulating tube extending downwardly from said upper receiver and being divided in two laterally and downwardly extending branches connected with said lower receivers adjacent their ends, and a horizontal tube connecting the lower ends of said branches with one another.

5. In combination with a boiler having within a casing a fire box and a combustion chamber, of a tubular receiver positioned horizontally in the upper portion of said combustion chamber, two tubular receivers arranged horizontally in the lower portion of said combustion chamber, one at each side of said fire box, said tubular receivers extending with their ends outwardly from said casing and being closed by individually removable cover plates, a plurality of series of water tubes connecting said lower receivers with said upper receiver, said water tubes being bent sinuously back and forth transversely from one side of said combustion chamber to the other, the water tubes in each series of tubes being spaced from one another to form slots through which the other series of tubes and the combustion gases may pass, and circulating tubes adjacent the front and rear ends of said receivers, and within said combustion chamber, each circulating tube extending downwardly from the bottom wall of said upper receiver and being divided in two laterally and vertically

downwardly extending branches connected with their lower ends with the top wall of said lower receivers, and a horizontal tube connecting adjacent their lower ends said branches with one another.

3. In combination with a boiler having within a casing a fire box and a combustion chamber, of a tubular receiver positioned horizontally in the upper portion of said combustion chamber, and projecting with its ends from said casing, a header arranged parallel to said tubular receiver and outside said casing, means connecting said header at a plurality of spaced points with said tubular receiver adjacent its ends, said header being provided between its ends with a plurality of flanged openings adapted to be connected with a heating system, two tubular receivers arranged horizontally in the lower portion of said combustion chamber, one at each side of said fire box, a plurality of series of water tubes connecting said lower receivers with said upper receiver, said water tubes being bent sinuously back and forth transversely from one side of said combustion chamber to the other, the water tubes in each series of tubes being spaced from one another to form slots through which the other series of tubes and the combustion gases may pass, and circulating tubes adjacent the front and rear ends of said receivers and positioned within said casing, each circulating tube extending downwardly from said upper receiver and being divided in two laterally and downwardly extending branches connected with said lower receivers adjacent their ends, and a horizontal tube connecting the lower ends of said branches with one another.

WILLIAM McGUINESS.
